METHOD OF MAKING AXLE HOUSINGS

Ernest Riemenschneider, Cleveland, Ohio, assignor to The Midland Steel Products Company, Cleveland, Ohio, a corporation of Ohio

Application December 31, 1930
Serial No. 505,876

10 Claims. (Cl. 29—153.1)

This invention relates to a welded axle housing and the method of making the same, and is in the nature of an improvement of the methods described in my copending applications Serial 5 Nos. 481,177, filed Sept. 11, 1930, and 486,971, filed Oct. 7, 1930.

In my copending applications above described the present methods of forming axle housings which are in general use are described and some 10 of the disadvantages and practices of these methods are set forth. The method herein disclosed of making axle housings and the housing formed by the practice thereof has several advantages over the prior methods and articles.

15 This method makes possible the manufacture of axle housings of uniform high quality and at the same time effects a considerable saving in cost.

Another advantage of my method is that it 20 eliminates all waste of stock and greatly reduces the amount of labor required. Furthermore, it may be practiced effectively with standard mill equipment and dies, all of which may be put to numerous other uses.

25 Another object of my invention is that the various steps of my method are comparatively simple and easy to apply, so that expert and highly skilled labor is not necessary, and the practice of the method is very adaptable to production in large quantities.

Another decided advantage of the present invention is that in an axle housing formed thereby the material is distributed so that it is effectively 35 utilized without waste, the extra material for greater wall thickness being provided where required without an excess of material in other portions. For example, the housing may be made by applying my method to a tube of constant wall thickness and yet the wall thickness of the enlarged central or gear portion of the housing will meet all requirements and the smaller ends of the housing will not be of exceeding great wall thickness, which may be difficult 40 to form and disproportionately strong, but on the contrary will be of the most desirable thickness for that particular portion.

In this manner any lines of concentration of stress are eliminated and the stresses are distributed 50 comparatively evenly throughout the entire housing.

The manner in which I accomplish these and other objects and advantages will be apparent from the following description in which reference 55 is made to the drawing by the use of

numerals, like numerals being used to designate the same parts in the various views.

In the drawing—

Fig. 1 is an elevation of an end of a length of tubing which forms the blank from which the 60 housing may be made.

Figs. 2 and 3 illustrate the next successive steps in the formation of the gear portion.

Fig. 4 is an elevation of a length of tubing, comprising a blank for the practice of a slightly 65 modified method from that illustrated in Figs. 1 to 3.

Fig. 5 illustrates the manner in which the blank of Fig. 4 is operated to form the housing.

Fig. 6 is the final step in either of the above 70 mentioned methods showing the finished central housing portion.

Referring first to Figs. 4 and 5 a section of tubing 1 of sufficiently large diameter to form the gear housing portion of the axle housing, as 75 later to be described, is used as the blank stock. This section of tubing is preferably seamless tubing or tubing welded for the full depth.

A portion of the blank above described, beginning a predetermined distance from the end is 80 reduced by swaging or otherwise to the diameter of the finished housing, as indicated at 2, leaving an enlarged end portion 3 which is to be formed into a gear housing portion. The central portion 3 is then slotted as indicated at 4, preferably 85 by diametrically opposite longitudinal slots extending a greater part of the length of the enlarged portion 3, thus bifurcating the same. The arms of the bifurcated end thus formed are then spread apart, as described in my copending applications Ser. Nos. 481,177, filed Sept. 11, 1930 and 486,971, filed Oct. 7, 1930, and formed into the flanged portion 6 of the finished housing. A similar half length of housing is then secured to the ends of the portion 6 by welding together the 90 ends 7 of the gear housing portion of the two half lengths of housing, as described in my copending application above identified.

As illustrated, I prefer that the gear housing portion gradually taper into the diameter of the 100 remainder of the housing, as indicated at 9, as this eliminates lines of concentration of stress and facilitates forming. The portion 3 being larger than the remainder of the housing furnishes sufficient material for the formation of the central gear housing portion of the axle housing, the material for the flanged portion 6 being derived from the length and diameter of the bifurcated end of the tubing. However, the portion 105 of the finished half length of the housing along 110

the planes indicated by the lines X—X and Y—Y in Fig. 6 cannot be derived from extra length of the enlarged portion 3, but requires additional material as the circumference in the plane Y—Y 5 and perimeter in the plane X—X are considerably greater than the circumference of the finished tubing.

Here it should be pointed out that if a blank of sufficient wall thickness to furnish the material 10 required along these planes were used, after reducing the diameter of the adjacent portion, as indicated at 2, to form the remainder of the housing, the wall thickness of the reduced portion would be somewhat increased. As a result 15 the reduced diameter portion of the housing would be disproportionately thick and tend to concentrate the stresses near the gear housing portion.

Furthermore, in choosing a tube to furnish sufficient wall thickness along the planes X—X and 20 Y—Y, the flanged portions 6 would be very thick walled, thus wasting considerable material and making the central gear portion disproportionately strong.

25 By my method, I contemplate effectively utilizing all of the stock which requires that the wall thicknesses at different portions be such that at no part is the housing disproportionately strong. I may approximate this construction by 30 making the slot 4 comparatively wide or by making it wider toward the outer end of the tubing, as indicated by the dotted line 8. This method, however, is not entirely satisfactory in many respects and I prefer however to use a tube of intermediate size, such as the tubing 10 of Fig. 1.

35 This tubing is small in diameter and too thin walled to render available the material required along the planes indicated by the lines X—X and Y—Y, but is greater in diameter than the finished 40 housing is to be. One end of this tube is reduced as indicated at 12 to bring it to the required diameter for the housing, the wall thickness of the stock being slightly less than required in the finished housing so that upon thickening due to reduction of diameter it will be the required thickness. The end portion 14 is left at the original 45 tube diameter for forming the central gear housing portion. As described, the amount of material available for the arm 6 is dependent primarily on the length of the portion 14. Consequently 50 this portion is left sufficiently long to furnish the material for the arms 6.

It will be seen that by using this tube of intermediate size the wall thickness of the portion 12 55 is not disproportionately thick, nor is the wall portion 14, but on the contrary, of the required thickness to facilitate forming the end flanges and arms 6. However, enough material is not provided for the required wall thickness of the 60 housing along the planes X—X and Y—Y, where extra material is required for reasons above described. In order to furnish this additional material therefore, the intermediate portion 16 of the tube is heated and subjected to endwise pressure, which bows the walls outwardly and forms an annulus 17. The wall thickness is reduced by increasing the diameter, but the walls may be practically the same thickness as the walls of the original tube or a predetermined desired thickness. 65 After the formation of the annulus, due to their tendency to upset under the endwise pressure. It should be noted that the amount of upset may be controlled somewhat by the degree of heating and degree of the axial compression. 70 From actual experience it has been found that

the only agents necessary to perform the expanding and thickening operation are heat and axial pressure on the two ends of the tube, said agents being so related as to effect the degree of enlargement and wall thickness desired. Assistance to this enlarging and thickening operation may be provided, if desired, by outward radial pressures exerted upon the inner walls of the portion to be enlarged by various means such as an expanding mandrel to assist in guiding the metal longitudinally of the enlarged portion as the tube is being axially compressed or upset to thicken the walls thereof. In this manner the extra material required along the planes X—X and Y—Y is provided.

80 The end of the stock, thus prepared, is slotted longitudinally with diametrically opposite slots indicated at 18 and the bifurcated ends spread apart to form the flanged arms 6. These arms are brought to final shape as described in my 85 above identified copending application.

90 For the purpose of illustration I have shown the ends of the slot extending substantially to the center of the annulus 17. This is satisfactory in case the central housing portion is to be 100 substantially circular. If a more elongated or elliptical shaped housing is required, the slot may extend further into the annulus 17 or terminate more to the right of the center thereof, depending upon the amount of material or length 105 required for the particular shape of arms 6. In other words the exact length of the slot is varied to meet the varying conditions in the requirements of the particular axle housing.

95 In some cases, especially in the method illustrated in Figs. 1 to 3, a better distribution of metal is obtained by punching a hole at the end of each of the slots 18, as illustrated by the dotted line 20. As a result of punching the hole 20 110 the edges of the slots are brought more nearly parallel to the outline of the annulus at these points so that the bifurcated ends are about the outline of the same width throughout their entire lengths. A further refinement includes punching a hole such as illustrated by the dotted line 19, the edges more gradually tapering into the slots 18. The walls of the combined 115 holes and slots are then substantially parallel to the outline of the annulus as illustrated in Fig. 3. Such holes also eliminate the tendency 120 of the tube to split at the end of the slot when the bifurcated portions are spread and produce an even gradual bend.

125 It is obvious therefore that by this method a half length of axle housing may be formed having substantially the correct wall thicknesses at the different portions and the arms 6, forming the gear housing portion, as well as the brake apron flange and integral bearing ring retainer may be of the correct wall thickness to facilitate 130 forming and to eliminate concentration of the stresses which occur along the lines of intersection of the heavy walled and thin walled portions of a member.

135 In the manners described, I may form a half length of axle housing from which a housing of comparatively constant strength throughout its full length may be formed.

I claim:

140 1. A method of forming axle housings which comprises forming a predetermined length of tubing near one end thereof into an outwardly bowed annulus having walls of substantially the same thickness as the tubing, bifurcating the 145 annulus and adjacent end with longitudinal slots 150

- extending to the free end of the tubing, spreading the bifurcated portions apart and forming them into outwardly extending arcuate forks and welding the ends of said forks to the ends of the forks 5 of another similar member held in axial alignment therewith. 80
2. A method of forming an axle housing, which comprises relatively reducing the diameter of a part of a length of tubing to form an end of larger 10 diameter than the reduced portion of the tubing forming a portion of the tubing intermediate the larger diameter end and the small diameter portion into an outwardly bowed annulus having walls of substantially the same thickness as the 15 tubing, bifurcating the enlarged end and part of the annulus with diametrically opposite slots, forming the bifurcated portions of the tubing into outwardly extending arms, and securing the member thus formed to a similar member by 20 welding the ends of the arms of the members together while holding the members in axial alignment. 90
3. A method of forming axle housings which 25 includes changing the relative diameters of an end portion and an adjacent portion of a length of tubing to form an end of greater diameter, subjecting the tubing to axial pressure to form a portion of the walls intermediate the enlarged 30 end portion and the remainder of the tubing into an outwardly bowed annulus having walls of substantially the same thickness as the original stock, bifurcating the enlarged end and annulus by diametrically opposite longitudinal 35 slots extending through the enlarged end and part of the annulus, spreading apart the bifurcated portions and forming the same into channel shaped outwardly extending arms to form the central gear housing portion of the axle housing, and completing the housing by welding the 40 ends of said arms to the ends of the arms of a similar member. 100
4. The method of forming axle housings which 45 includes providing tube stock with an enlarged end and bifurcating the enlarged end by diametrically opposite longitudinal slots, the walls defining each of said slots being spaced apart and diverging from the enlarged outer end of the tube inwardly, spreading apart the bifurcated portions and forming the same into outwardly 50 extending arcuate arms, and securing the member to a similar member in axial alignment therewith by securing together the end portions of the arms of one of said members to similar portions of the other. 110
5. A method of forming axle housings which 55 includes reducing the diameter of a portion of a length of tubing spaced from the end whereby an end of larger diameter than the remainder of the tubing is formed, subjecting the tubing to axial pressure to form a portion intermediate the large end and the remainder of the tubing into an outwardly bowed annulus, whereby the thickness of the annulus walls are decreased due to increased diameter and concurrently increased in 60 thickness, due to the upsetting by axial pressure, bifurcating the end portion and annulus by longitudinal slots extending from the outer end through the enlarged end and partially through the annulus, spreading apart the bifurcated por- 115
- tions and forming the same into outwardly extending flanged arms and securing the member thus formed to a similar member by securing together the end portions of the outwardly extending arms of said members. 85
6. A method of forming axle housings from tubular stock which includes the steps of forming a portion of the tube adjacent one end into an outwardly bowed annulus having a wall thickness substantially equal to that of the original stock, slotting the annulus with diametrically opposite longitudinal slots extending from said end of the tube into said annulus and spreading apart the bifurcated portions and forming such portions into channel-shaped cross section. 95
7. A method of forming axle housings from tubing, which includes the steps of subjecting a length of the tubing to axial inwardly directed pressure to bow outwardly a portion of the tube adjacent one end to form an annular portion having wall thickness substantially equal to that of the original tubing, and bifurcating the annular portion and adjacent end with longitudinal slots extending to the free end of said tube, and spreading the longitudinal portions apart and forming them into U-shaped cross section. 100
8. A method of forming an axle housing which comprises relatively changing the diameter of a length of tubing to provide an enlarged end and a smaller end with an intermediate tapered portion of substantial length, bowing outwardly a portion of the enlarged end adjacent said tapered portion whereby its wall thickness is substantially equal to that of the original tubing, bifurcating the enlarged end of the tubing, spreading apart the bifurcated portions and forming such portions into outwardly extending arcuate arms, and connecting said arms to corresponding arms of another similar member held in axial alignment therewith. 105
9. A method of forming an axle housing which comprises relatively changing the diameter of a length of tubing to provide an enlarged end and a smaller end with an intermediate tapered portion of substantial length and of wall thickness substantially equal to that of the original tubing, bifurcating the enlarged end of the tubing, spreading apart the bifurcated portions and forming such portions into outwardly extending arcuate arms, and connecting said arms to corresponding arms of a similar member held in axial alignment therewith. 120
10. A method of forming axle housings which comprises relatively changing the diameter of a length of tubing to provide an enlarged end and a smaller end with an intermediate tapered portion of substantial length and wall thickness slightly greater than that of the original tubing, bowing outwardly a portion of the enlarged end adjacent said tapered portion while upsetting the same whereby its wall thickness is substantially equal to that of the original tubing, bifurcating the enlarged end of the tubing, spreading apart the bifurcated portions and forming such portions into outwardly extending arcuate arms, and connecting said arms to corresponding arms of a similar member held in axial alignment therewith. 125
